PHILIP D. NORTHCRAFT, OF THURSTON COUNTY, WASHINGTON TERRITORY.

Letters Patent No. 96,027, dated October 19, 1869.

IMPROVEMENT IN SHINGLE-MACHINE.

The Schedule referred to in these Letters Patent and making part of the same

To all whom it may concern:

Be it known that I, PHILIP D. NORTHCRAFT, of Thurston county, Washington Territory, have invented certain new and useful Improvements in Shingle-Machines; and I do hereby declare that the following is a full and exact description thereof, reference being had to the accompanying drawings, making a part of this application.

My invention consists in providing a shingle-machine with a drag-lifter, constructed and operated in the manner and for the purposes hereinafter more fully explained.

My invention further consists in the peculiar construction and operation of the stop-frame, as hereinafter explained.

My invention further consists of a knife and roller, on the end of the carriage, and operating in conjunction with the stop-frame, as and for the purposes hereinafter set forth.

My invention further consists in forming on the outside faces of the carriage a groove, for operating the lower shaving-knife and stop-frame, with respect to each other, and in the manner and for the purposes hereinafter explained.

And my invention further consists in providing, in the upper rails of the frames, grooves, for operating the gate-head and right-angled clamps, as will be presently explained.

Figure 1 is a side view of my machine, with the carriage in two positions;

Figure 2 is a longitudinal vertical section through the centre;

Figure 3 is a side view, with side of the frame off, exposing the side of the carriage;

Figure 4 is a vertical cross-section, taken at the line *x x*, fig. 1;

Figure 5 is a vertical cross-section at the line *y y*, fig. 1; and

Figure 6 is a top view of the exit end of the machine, broken off.

Similar letters of reference denote parts in the several views.

A A, &c., are standards, upon which the frame and carriage are mounted.

Said standards extend upward a suitable distance, and are provided with side rails B B, which have cut therein, on their interior faces, a groove, *a*, and another shorter one, *b*. The bed of the latter is cut on an incline from rear to front at its extremity.

The frame of the machine consists of two side rails C C, one of which has cut, on the exposed side, a groove, *c*, and both have a slot cut vertically through, as seen at *d d*, fig. 6.

The one having the groove *c* is also cut away a

short distance, as seen at *e*, fig. 1, for the purpose hereinafter shown.

The sides C C are secured to a bottom piece, D, made in two sections, one (the forward) being a little higher than the other, and a channel, E, left between them.

This channel is underneath the shaving-knife, and is intended for the exit of the shaving.

These bottom pieces D have arranged thereon rails or ways F F, fig. 5, upon which the carriage travels.

Between the side rails C C, and at the proper distance from the forward end, are arranged two knives, *f f*, with their sharp edges toward the front end of the machine. The upper one is permanently attached in one position, between the rails C C, and the lower one is returned at the ends, follows up in a slot prepared for it in the rails, as seen at *o*, and into the groove *i*, in the rails G, so that the said knife is raised and lowered, as the groove travels over the bent end of the knife, as will be presently explained.

The top of the rear section of bottom D is bevelled with the same inclination as is desirable for the shingle, beginning at the point where the stop *g* penetrates the said bottom, as will be presently explained.

The carriage is composed of two side rails G G, secured by a cross-piece, H, at one end, another, I, at the other.

These rails are grooved, to ride upon the ways F F, and are cut away a proper distance, to pass over the knives *f f*.

Lugs *h h* are secured to the rails, for the purpose of actuating a button, *k*, secured by a pivot to the top of each of the side rails C C, and swivelling thereon.

The rails G G are grooved on their exterior surfaces, as seen at *i*, and travel over the bent end of one of the lower knives *f f*, and a pin in the frame of the stop *g*.

At the rear of the carriage is secured a shaving-knife, *k*, in the same plane with the top side of the bottom D, just in front of the stop *g*, or where the bevel begins.

The edge of the knife is set toward the front of the machine, and immediately in front of said edge is arranged a roller, J.

Said roller is mounted in a frame, L, which moves up and down in slots in the side rails of the carriage, and is governed by a spring, *l*, secured to the cross-piece I.

Behind said knife are secured to the end of the carriage two brackets *m*, in the lower extremities of which is mounted a cylinder or rod, *n*, having a bent arm, *o*.

One end of the cylinder or rod *n* is provided with crank-lever or arm *p*, having in its upper end an eye, wherein is secured a small rod, *r*, which passes back, and is secured permanently at one point on the circumference of the drag-lifter *M*, by a short upright, *q*.

This drag-lifter is secured to the top of the carriage by staples *s*, and is free to rotate therein.

One end of the drag-lifter is provided with a short lever, *N*, having one end bent at right angles, the bent end adapted to move in the groove *c*, of the rails *C*.

A block-holder, *O*, as seen more clearly at figs. 2 and 4, is arranged securely between the rails *G*, a distance from the cross-piece *H*, equal to the length of a shingle.

Said holder is provided with loops *t t*, through which passes a drop or retaining-rod, *P*, having thereon a shoulder or stop, *r*.

The top of the block-holder is provided with two pins, *w w*, which move into slots in a head-piece, *Q*, the head-piece being thus allowed to move up and down upon the pins *w w*.

The ends of this head-piece are provided with pins, which move along in the grooves *a*, in rails *B*, and it is also provided with two right-angled clamps or springs, as clearly seen at Figure 7, which embrace the drop-rod *P*, or not, as becomes necessary in the course of operation.

The stop *g* is mounted upon the bottom *S* of a frame, *T*, the side of the frame moving vertically in the slot *d* of the rail *C*.

On one of the sides of this frame *T* is secured a pin, *x*, and on the interior of both the upright sides of the frame is another pin, which moves in the grooves *i*, of the rails *G* of the carriage.

Underneath the said frame is arranged one or more springs, *y*, for the purpose to be explained.

To the side rail *C* is pivoted a lever, *W*, which lies upon the pin *x* on the "stop"-frame, and is raised and lowered thereby.

To the drag-lifter is secured a drag, *U*, which, when the machine is ready to start, extends a short distance beyond the back edge of the knives *f f*.

To this is loosely pivoted another, *V*, extending a short distance past the end of the carriage-frame. They are both bent down at right angles, like a hook, as clearly seen in the drawings.

On one side of the bent portion of *U* is a stop, so that the drag *U* may rise a short distance before the other, *V*, is effected.

The operation of my improved machine is as follows:

The carriage being drawn back, ready to start, the block from which the shingles are to be cut is placed upon the bottom *D*, and between the cross-piece *H* and block-holder *O*. The drop-rod *P*, which is supposed to be heavy enough to hold the block steady against the bottom, is then allowed to drop upon the top of the block. The machine being now ready to start, power is applied to the carriage, it is driven along upon the ways *F F*, the block extending below the bottom edge of the holder *O*, is forced against the edges of the knives *f f*, the upper one splitting the shingle off, and the lower shaving the under side of the shingle.

The lower knife is elevated as the carriage travels, by the incline in the groove *i*, which travels over the bent end of the knife, and thus the shingle is shaved off on one side, slightly bevelled, and smooth.

When the carriage has travelled far enough to commence to split the block, the cross-head of the holder *O* begins to rise in the groove *a*, and the right-angled clamps, having passed out of the slots *b*, are pressed against the rod *P*, and grasp it, so that the cross-

head *Q* carries the said rod up with it, leaving room underneath for the knife to accommodate itself to the grain of the block.

When the carriage has travelled far enough to cut clear through the block, the rear lugs *h* strike the bevelled sides of the buttons *K*, and cause them to swivel, so that the opposite ends are thrown from over the slots *d*, which they cover, and allow the stop-frame sides *T* to fly up, (the pins on the interior of said frame, which move in the slots in the carriage-frame, having found a channel between said grooves, through which to pass,) and bringing with it the stop *g*, the pins *x*, on the outside of the stop-frame, lifting the lever *W*, which strikes the straight end of the short lever *N*, lifting the same, which revolves the drag-lifter or cylinder *M*, causing it to lift the three drags *U*, *V*, and *o*, and, at the same time, depresses the bent end of the lever into the end of the groove *c*.

The carriage is now started back, the lever *N* travelling within the groove *c*, keeps the drags all elevated until the carriage gets back to its starting position, the groove in the carriage-frame travelling over the pins in the stop-frame bring it down, and the forward lugs *h h*, striking the inside of the buttons *K K*, at the moment that the stop-frame has been brought clear down, forces them back to their original position over the slots *d*, and, consequently, on top of ends of the stop-frame, at the same instant that the bent end of the lever *N* has arrived at the exit of the channel *c*, and the drags, by their own weight drop, the first one, *U*, dropping on the half-finished shingle, which was left back of the knives *f f*, the right angle clamps in the cross-head have been released, and the drop-rod *P* is again on top the block. The carriage is again started forward, the drag *U* carries the shingle (with its under side finished) along, while another is being cut and shaved, and when the second is in the condition we found the first, the first has been carried to the end of the trough upon the bevelled bottom, the lugs have struck the buttons, and the stop has shot up, and now prevents the half-finished (first) shingle from going back.

The carriage is again started back, as before, when the roller in its spring-frame holds the shingle down, while the knife *k* begins to shave the top side, the shaving passing out over the top of the knife, and over the roller *n*, with its drag *o*. The carriage is sent clear back, and the operation commenced again, all the drags dropping when the carriage has gotten home, *U* takes hold of the second shingle, *V* takes the shaving from the first shingle, and *o* takes the first shingle itself.

The operation renewed again, the drags carry the finished shingle and shaving out of the way and bring the second one along to occupy the place vacated by the first, while the third is being cut; and so on, the shavings taken from the under side passing out between the sections *D* of the bottom.

Having described the construction and operation of my improved shingle-machine,

What I claim as new, and desire to secure by Letters Patent, is—

1. The drag-lifter *M*, secured to the carriage-frame, by staples *S*, and travelling with the carriage, the lever *N*, and drags *U*, *V*, and *o*, arranged as described, and operated by the groove *c*, lever *W*, and stop-frame *S*, and its pin *x*, substantially as and for the purposes set forth.

2. The upper rails *B*, provided with the slots *a b*, constructed as described, in combination with the gate or block *O*, with its vertically moving head *Q*, provided with pins, to travel in groove *b*, and right-angled clamps *z*, rod *P*, and loops *t t*, all arranged and operating in the manner and for the purposes set forth.

3. The stop-frame *S*, provided with the stop *g* and pin *x*, performing the double duty of arresting the shingle, and lifting the drags, automatically, in the manner and for the purpose set forth.

4. In combination with the above, the knife *k* and roller *J*, as and for the purposes set forth.

5. The carriage-frame, moving inside of the ways, and provided on their exterior sides with the grooves *i*, so constructed that one end shall move over and raise and lower the lower shaving-knife *f*, and the

other travel over the pin *x*, on the stop-frame, raising and lowering it automatically, and with reference to the movement of the knife *f*, in the manner and for the purpose set forth.

In testimony whereof, I have hereunto set my hand and seal, this 24th day of July, A. D. 1869.
